UNITED STATES PATENT OFFICE.

ELMER N. DOWNES, OF CHARLOTTE, NORTH CAROLINA, ASSIGNOR TO MCCLAREN RUBBER COMPANY, OF CHARLOTTE, NORTH CAROLINA, A CORPORATION OF DELAWARE.

DESIGN FOR A NONSKID TIRE TREAD.

Application filed February 24, 1922. Serial No. 882. Term of patent 14 years.

To all whom it may concern:

Be it known that I, ELMER N. DOWNES, a citizen of the United States, residing at Charlotte, in the county of Mecklenburg and State of North Carolina, have invented a new, original, and ornamental Design for a Nonskid Tire Tread, as shown in the accompanying drawing, forming part of this specification.

In said drawing Figure 1 is an exterior face or edge view of part of the tire showing the peculiar bas relief ornamental configuration thereof. Fig. 2 is a transverse sectional view on line 2—2, Fig. 1, and Fig. 3 is a transverse sectional view on line 3—3, Fig. 1.

The design consists of four parallel rows of diamond shaped portions A extended circumferentially of the tread of the tire and

spaced apart, the alternate diamond shaped portions inclining both in the rows extending longitudinally of the tire and in the rows extending transversely of the tire rendering a distinctive appearance and at the outer side of the portion A is a longitudinal portion having a series of forwardly projecting curved portions B and similar upwardly projecting intermediate portions C.

The design is in relief and extends longitudinally and circumferentially of the tire tread as indicated in the drawing.

I claim:

The ornamental design for a non-skid tire tread as shown and described.

ELMER N. DOWNES.
